UNITED STATES PATENT OFFICE

ABRAHAM L. LEVIN, OF NEW YORK, N. Y., ASSIGNOR TO LESTEIN CORPORATION OF AMERICA, A CORPORATION OF NEW YORK

RADIO RECEIVING APPARATUS

Application filed May 22, 1925. Serial No. 32,197.

This invention relates to radio receiving circuits and more particularly to a construction of electron tube apparatus which does not require the employment of primary and secondary batteries for its operation.

The object of the invention is to provide a construction of electron tube which is particularly adapted for operation from energy supplied from the usual house lighting circuit without the employment of primary or secondary batteries.

This invention utilizes a construction of electron tube in which a plurality of independent electrodes are provided, one of the electrodes being a heating member arranged to be energized from the lighting circuit. Surrounding the heating member there is located an insulating tubular member on the outer walls of which is deposited an electron emitting coating such as barium or strontium or some other combination of elements having electron emitting properties. Interiorly arranged within the insulating tube surrounding the heating member there is provided a spiral metallic coil or resistance member having its ends passing through the walls of the insulating tubular member and substantially insulated from the electron emitting coating on the surface of the tubular member. One end of this coil passes to one terminal exterior of the tube while the opposite end of the coil passes to a plate electrode arranged adjacent the electron emitting coating. While I have shown the spiral coil as positioned interiorly of the insulating tube I desire that it be understood that the position of this coil may be varied and I do not desire to be limited to the particular location of the coil as will be hereinafter described. A grid electrode or control member is positioned within the tube adjacent the electron emitting coating and in circuit therewith is provided a high resistance element internally located within the vessel which contains all of the electrodes. I have found that this resistance in close proximity to the control electrode functions to produce more uniform operation of the tube. The terminals of the heating member are brought outside of the closed vessel in which the tube

electrodes are contained and are connected across the line circuit. The electron emitting coating is electrically connected in circuit with one side of the heating member which defines the potential of the electron emitting coating as that of one side of the supply line. The plate member is connected through the coil device to the output circuit of the system which connects to the opposite side of the supply line. In this manner an effective difference of potential exists between the plate electrode and the electron emitting coating. Similarly, the potential existing across the heating member is substantially that which is delivered by connections from the current supply apparatus. The tube may be employed in a variety of electrical circuits, but I have illustrated the same in connection with a radio receiving circuit where the incoming signalling energy is impressed across the input terminals of the tube. The incoming signalling currents are virtually impressed across the circuit existing between the electron emitting coating and the grid electrode. I have termed the electron emitting coating the fifth element of my tube construction. It will be observed that the electron emission is not obtained in the usual manner by actually passing a heating current through the electron emitting body, but is obtained by radiation or electron bombardment from the heater member energized as hereinbefore explained from the house lighting circuit. The electron emission from the electron emitting coating of the fifth element normally takes place in a direction toward the plate electrode and the internal coil device by reason of the fact of their normal positive polarization from the line circuit. The internal coil device by reason of its positive polarity normally tends to attract the electrons from the heater member in the direction of the fifth element thereby increasing the bombardment of the fifth element. A by-pass circuit is provided in shunt with the circuit including the heater member so that high frequency signalling currents may be usefully employed only for effecting the variation in electron emission from the electron emitting coating by change in polar-

ity of the grid member. The plate electrode is connected in the output circuit of the tube and may lead to a succeeding tube in cascade arrangement or may have a responsive device connected directly in the output circuit. The difference in potential in the output circuit is substantially that delivered from the line system as hereinbefore explained.

My invention will be more fully described 10 hereinafter in the following specification by reference to the accompanying drawings forming a part thereof, and in which:

Figure 1 is an elementary diagram showing the arrangement of my tube construction 15 in a simplified form of radio receiving circuit;

Fig. 2 is a diagrammatic view showing the arrangement of the electrodes of my tube construction;

Fig. 3 is a perspective view of the electron emitting body employed in my tube construction partially broken away to show the interior construction thereof; and,

Fig. 4 is a view of one of the commercial 25 embodiments of the tube construction of my invention.

Referring to the drawings in more detail, reference character 1 designates a receiving antenna system having a ground system 2 and including a primary inductance 3 in circuit therewith. A secondary winding 4 is coupled with the primary winding 3 and is tuned by a suitable tuning circuit designated at 5. For the purpose of more clearly setting forth my invention I have shown in Fig. 1 a single tube functioning both as a detector and an amplifier of the incoming signalling energy. The tube is represented as enclosed within a vessel 6. Centrally positioned within the vessel I provide a heating member or element 7 having terminals 7a and 7b extending exteriorly of the tube. Surrounding the heater element I provide the insulating cylindrical member 8 which may take the form of a tube of glass or other vitreous material. Internally arranged within the tube 8 I provide a coil member 9, one end of which passes outwardly through the wall of the tube member 8 through an insulating bushing designated at 10 and connects to the plate member 11. The other end of the coil member 9 passes through an insulating bushing 12 and extends exteriorly of the tube to a terminal 14. Upon the exterior of the tubular member 8 I provide an electron emitting coating 15 formed of any suitable material as I have previously described. This material may be a barium or strontium salt or other elements may be used to form a coating directly upon the surface of the insulating tube 8. The heater member 7 by direct radiation or electron bombardment operates to heat the tube 8 and the electron emitting substances 15 produce a constant electron discharge within the vessel 6.

The electron bombardment of the tube 8 is facilitated by the coil 9 which is charged positively with respect to the element attracting the negative electrons in the direction of the electron emitting coating 15. Coil member 9 has its turns substantially spaced apart as illustrated for presenting minimum effective area or exposure to the exterior coating 15, while offering substantial attractive force immediately adjacent the heater 7 for facilitating the heating of the insulated tube 8. As has been shown, the plate member 11 presents a large area adjacent the electron emitting coating 15 and thus overcomes any substantial effects of coil 9 upon the electrons from coating 15. The tube 8 serves as a shield against any appreciable effects of coil 9 on the electron emission from coating 15. Arranged adjacent the electron emitting coating 15 there is mounted the grid or control member 16 having a resistance element 17 arranged in circuit therewith and interiorly positioned within the tube intermediate the tube and the input treminal 18 thereof.

The power supply for the cathode and anode circuit is either rectified alternating current or direct current. In order to accurately control the energy supplied to the electron tube circuit I interpose in the line a pair of substantially equal impedances 34 and 35 variably operative from a single control as designated by reference character 36. To limit the value of the energy supplied to the electron tube apparatus I provide additional fixed impedances 37 and 38 in the line circuit. In order to more fully exclude hum and other undesired interference in the receiving circuit a reactance 39 is connected in the supply circuit. In order to by-pass radio frequency currents, that is, currents of the signalling frequency, I provide a condenser 40 in shunt with the heater member or cathode 7 by which the radio frequency currents may be effectively utilized. The input terminals of the tube are connected in the tuned receiving circuits 4-5 with a grid leak and grid condenser 41 interposed in circuit with the grid member 16. The variations in the signalling currents are impressed directly across the electron emitting body 15 and the control member 16. The plate electrode 11 through the intermediary of the coil member 9 is connected in the output circuit through terminal 14 and may include any desired form of responsive device 42 or may connect to the input circuit of a succeeding tube of a series and to one side of the current supply line designated at 43. It will be observed that the electron emitting body 15 is connected through a lead 44 with one side of 7a of the heater member 7. The potential from the current supply system is impressed across the heater member 7 and also across the electron emitting body 15 and the plate electrode 11 in such manner that

electron discharge from the electron emitting body 15 tends to take place in the direction of the plate electrode 11. The variation in the signalling energy becomes effective to vary the degree of charge and polarity of the grid 16 resulting in the control of the electron flow from electron emitting body 15 to plate 11 thereby controlling the energy in the output circuit of the apparatus.

10 A clearer conception of the electron emitting body 15 will be obtained from the construction illustrated in perspective view in Fig. 3 of the drawings wherein the tubular member 8 is provided with the coating 15 of the electron emitting substance. The coil member 9 interiorly of the tube passes outwardly, as hereinbefore explained, through the walls of the tubular member 8 through bushings 10 and 12 without contacting with 20 the electron emitting substance 15 and is charged at similar positive polarity as is the plate electrode 11. By this arrangement the plate electrode 11 operates to attract electrons from the electron emitting coating 25 15 while the coil member 9 operates to attract electrons from the heater 7. The heater member 7 is shown arranged within the tubular member 8.

In the commercial embodiment of the tube 30 construction shown in Fig. 4 the leads 18, 7a, 7b and 14 pass downwardly through the base of the tube 17 as represented at 45 and connect to a set of four contacts on the base of the tube. The tube may be inserted in 35 a standard electron tube socket of the usual bayonet slot type. The electrodes are supported interiorly within the tube by an inwardly extending portion 46 upon which is mounted the plate electrode 11, the fifth 40 element, or tubular member 8, and the heater member 7. I have designated the grid 16 as being spirally arranged around the electron emitting body 15. While I have shown the tube construction in certain specific embodiments I desire it to be understood that 45 the details of the construction may be varied without departing from the spirit of my invention.

While I have described my invention in 50 certain particular embodiments, I desire that it be understood that the principles thereof may be embodied in a number of different forms and that I intend no limitations upon the invention other than those imposed by 55 the scope of the appended claims.

What I claim and desire to secure by Letters Patent of the United States is as follows:

1. An electron tube comprising an evacuated vessel, a heater within said vessel, a 60 thimble member having high electrical resistivity and good heat conductivity surrounding said heater, a winding having its turns lying in contact with the interior walls of said insulating member and having connections whereby it may be electrically charged

to effect bombardment of electrons from said heater radially toward said insulating member, an electron emitting coating carried by the exterior walls of said member and grid and plate electrodes within said vessel, said grid and plate electrodes being arranged to control the bombardment of said plate electrode by electrons radiated from said electron emitting coating. 70

2. An electron tube comprising an evacuated vessel, a heater extending centrally within said vessel, a thimble member enclosing said heater, said thimble member comprising insulation material having high heat conductivity, a coil member having its turns wound in contact with the interior walls of said thimble and having connections whereby it may be electrically charged to attract electronic bombardment from said heater radially in the direction of said thimble for raising the temperature thereof, an electron emitting coating extending over the exterior walls of said thimble and grid and plate electrodes within said vessel, said grid electrode operating to control the bombardment of electrons from said electron emitting coating against 85 said plate electrode. 90

3. An electron tube comprising an evacuated vessel, a heater, an insulating thimble enclosing said heater, said thimble having a high degree of heat conductivity, a multiple turn coil having its turns wound in contact with the interior walls of said thimble and having connections whereby it may be electrically charged to attract electronic bombardment from said heater radially in the direction of said tubular member for raising the temperature thereof, an electron emitting coating carried upon the external walls of said thimble, and grid and plate electrodes disposed adjacent the electron emitting coating on said thimble whereby electrons emitted by said electron emitting coating may be directed against said plate electrode and the bombardment thereof varied under control 100 of said grid electrode. 105

4. An electron tube comprising an evacuated vessel, a heater within said vessel, an insulated tubular member substantially in the form of a thimble surrounding said heater 115 and having an electron emitting coating thereon, grid and plate electrodes within said vessel arranged adjacent said electron emitting coating and a coil member disposed within said tubular member and series connected with said plate electrode, said coil member operating at a potential more positive than said heater while said plate operates at a potential more positive than the electron emitting coating on said tubular member. 120

5. An electron tube comprising an evacuated vessel, a heater within said vessel, an insulated cylindrical member substantially in the form of a thimble surrounding said heater, an electron emitting coating on the 125

exterior walls of said cylindrical member, a grid and plate electrode adjacent said electron emitting coating within said tube, a grid terminal, a plate terminal, and a coil member disposed within said cylindrical member and connected in series between said plate electrode and the plate terminal of said tube, said coil member having its turns contacting with the interior walls of 10 said cylindrical member.

6. An electron tube for operation from relatively high potential comprising an evacuated vessel containing a heating element, a heat conducting envelope substantially in the shape of a thimble surrounding said heating element, an electron emitting coating on the exterior walls of said envelope, a control electrode, a plate electrode, and an electrode disposed concentrically 15 within said heat conducting envelope surrounding said heating element and separated from said electron emitting coating by the walls of said envelope and electrically connected with said plate electrode, said concentrically disposed electrode having substantially less exposure to the electron emitting coating on the exterior walls of said envelope than the exposure of said plate electrode with respect to said coating where- 20 by electrons emitted by said heating element are caused to bombard said heat conducting envelope for raising the temperature thereof and developing electron emission from said electron emitting coating, said emission being directed toward said plate electrode.

7. An electron tube comprising an evacuated vessel, a heating member therein, an envelope of heat conducting material substantially in the shape of a thimble surrounding said heating member, an electron emitting coating on the exterior walls of 40 said envelope, a plate electrode within said vessel adjacent said electron emitting coating, a control electrode within said vessel 45 adjacent said electron emitting coating and a coil member interiorly of said envelope and electrically connected with said plate electrode, said coil member having connections whereby it may be electrically charged 50 for facilitating bombardment of said envelope by electrons from said heating member causing electron emission from said electron emitting coating in the direction of said plate electrode, said plate electrode 55 having substantially greater exposure to said electron emitting coating than said coil member.

8. An electron tube comprising an evacuated vessel, a heating member within said 60 vessel, a heat conducting envelope of substantially thimble shape surrounding said heating member and having an electron emitting coating on the exterior walls thereof, a control electrode within said vessel, a plate electrode, and a coil member carried 65

by the interior walls of said envelope and having less exposure with respect to said electron emitting coating than the exposure of said plate electrode with respect thereto, said coil member being electrically connected to said plate electrode for causing electron bombardment of said heat conducting envelope for producing secondary emission therefrom.

9. An electron tube comprising an evacuated vessel, a heating element within said vessel, a heat conducting envelope surrounding said heating element, an electron emitting coating on said envelope, grid and plate electrodes within said evacuated vessel and a spiral member within said heat conducting envelope electrically connected to said plate electrode and having less exposure to said electron emitting coating than the exposure of said plate electrode with respect thereto whereby electrons emitted from said heating element effect secondary emission of electrons from said electron emitting coating for bombardment of said plate electrode.

In testimony whereof I affix my signature.
ABRAHAM L. LEVIN.
